2 SHEETS—SHEET 2.

UNITED STATES PATENT OFFICE.

JOHN CHOMA, OF CARNEGIE, PENNSYLVANIA.

COLLAPSIBLE BED.

1,262,751.

Specification of Letters Patent. Patented Apr. 16, 1918.

Application filed October 24, 1916. Serial No. 127,357.

To all whom it may concern:

Be it known that I, JOHN CHOMA, a subject of the Emperor of Austria, and a resident of Carnegie, in the county of Allegheny and State of Pennsylvania, have invented certain new and useful Improvements in Collapsible Beds, of which the following is a specification.

This invention relates to improvements in collapsible beds, and has as its principal object, the provision of an article of furniture which may be extended both longitudinally and laterally so as to afford a bed, suitable for one or more persons, as may be preferred, or collapsed into relatively small compass, resembling an ordinary chest.

A further object is to provide such article with means manually manipulated from the end thereof, whereby the structure may be extended lengthwise and in addition thereto, extended sidewise as well, and finally, to provide an article of the class described which is capable of containing the several articles used in connection with a bed, as springs, mattress, blankets, pillows, and the like, when in a folded or collapsed position, the same being readily portable from place to place as may be desired.

These and other like objects are attained by the novel design, construction and combination of parts hereafter described and shown in the accompanying drawings, forming a material part of the specification, and in which:—

Fig. 1 is a top plan view of the structure shown in an extended position, the mattress and bedding being removed.

Fig. 2 is a partial sectional view taken on line 2—2 of Fig. 1.

Fig. 3 is a transverse sectional view taken on line 3—3 of Fig. 1.

Fig. 4 is a front elevation showing the article in a folded position, and

Fig. 5 is an end view of the plates unfolded.

The device comprises a pair of oppositely disposed side plates 10, to the front corners of which are connected, by hinges 11, a pair of doors 12 adapted to fold inwardly when the device is in a collapsed position as indicated in Fig. 4.

The end plates 10 have rigidly engaged with them pairs of rack bars 14 and 15, the

teeth 16 and 17 of which engage upon opposite sides of the pinions 18 and 19, arranged upon stems 20 and 21, on which are secured bevel pinions 22 and 23 meshing with mating pinions 24 and 25, mounted upon a transverse shaft 26, carried in bearings 27, supported by the plate 13, in turn fixed between the upper parts of the stationary back and front plates, respectively 48 and 48' the bearings having between them a bevel pinion 28 meshing with its mate 29 secured on the end of a horizontal shaft 30 provided with a clevis joint 31 engaging the shaft 32, which extends outwardly beyond the end plate 10, where it is furnished with a crank 33.

In addition to the racks 14 and 15, supporting bars 35 are rigidly attached to the extreme upper front corner of the end plates adjacent to the hinges 11, the bars 35 being telescopically receivable within a fixed tube 36 which extends longitudinally at the upper front edge of the article.

From the foregoing it will be understood that when the crank 33 is turned, causing the pinions 18 and 19 to rotate, that the rack bars 14 and 15 are moved in opposite directions, in such manner as to carry the plates 10 outwardly, thus extending the article lengthwise, or bring them inwardly toward a common center.

At the extreme front of the doors 12 are connected similar rods 38 having downturned ends 39, formed in the manner of a hook and engageable with clips 40, secured to the inner front edge of the doors 12, the opposite ends of the rods 38 being telescopically received within a tube 42, in turn being engaged by transverse rods 44, slidably held within tubes 45, secured to the longitudinal tubes 36, at one end, and to the fixed back 48 of the article at the other end, it being understood the stationary or fixed part of the article, consists of the flooring 62, the hinged cover 65, front and rear elements 48 and 48' together with the shelf or plate 13.

The tube 42 is extended laterally by means of racks 50, one end of which is rigidly engaged with the tube and the other held in operative relation to pinions 51, mounted on a shaft 52, housed in bearings 105 formed with the transverse tubes 45, one

end extending through and having engaged with it a clevis joint 56 connecting with an extending shaft 57, provided with an operating crank 58 at the end.

5 The shafts 32 and 57, when extended at length, pass outwardly through the edge of the plates 10, in slots 59 and 60, permitting the shaft to be folded when the article is in a collapsed position, or rotated when horizontal, whereby the front part of the article may be extended or retracted.

10 A fixed bottom plate 62 extends below the main portion of the article between the back plate 48, to the upper edge of which 15 is attached by means of hinges 64, a cover plate 65, adapted to overlie the structure when in a closed position.

15 From the foregoing, it will be seen that an article of furniture is provided which 20 may be extended lengthwise to form a couch and extended sidewise so that the couch may be used for more than one person, the various bedding material being disposable within when the article is folded 25 into its smallest compass.

Having thus described my invention, what I claim as new, and desire to secure by Letters Patent, is:—

In a collapsible bed, the combination with a frame work having movable end elements, 30 pairs of rack bars attached to the inner side of said end elements, a pinion operatively engaged with each of said pairs of rack bars, means for transmitting rotary motion to said pinions, tubular guides for said end elements, said tubular guides being a component part of the frame, leaves hinged to the vertical front edge of said end elements, said leaves being foldable toward each other or extended to form a bed support, 40 rods for holding said end elements when in an extended open position, said rods being telescopically engaged one with another, and means for moving said side elements laterally to or from said frame. 45

Signed at Carnegie, in the county of Allegheny, and State of Pennsylvania, this 16th day of September, 1916.

JOHN CHOMA.
